CLAIM

The ornamental design for an insole, as shown and described.

DESCRIPTION

FIG. 1 is a top perspective view of an insole showing our new design;

FIG. 2 is a bottom perspective view thereof;

FIG. 3 is a bottom plan view thereof;

FIG. 4 is a top plan view thereof;

FIG. 5 is a lateral elevation view thereof;

FIG. 6 is a medial elevation view thereof;

FIG. 7 is a rear elevation view thereof; and,

FIG. 8 is a front elevation view thereof.

The broken lines in the figures illustrate portions of the insole that form no part of the claimed design.

1 Claim, 8 Drawing Sheets
